MACHINE FOR NIBBLING OR PUNCHING
METAL AND OTHER SHEETS

George Henry Webb, Edgware, England

Application January 10, 1939, Serial No. 250,243
In Great Britain April 27, 1938

15 Claims. (CL. 164—47)

This invention relates to nibbling machines having a reciprocating punch of suitable section co-operating with a die of appropriate shape carried by a relatively fixed framework or support, of the known type in which the relatively fixed framework or support carrying the die comes to the rear of the reciprocating punch and adjacent thereto, so that relatively to the workpiece it can follow the said punch through a cut, caused by successive nibblings with an adequate feed.

The invention refers more particularly, although not exclusively, to such devices of a portable nature adapted to be moved (by hand or otherwise) in relation to the workpiece being operated upon. Thus, for example, such devices can be utilised for cutting sheet metal by being moved in relation thereto through a desired path.

In general, according to the principal feature of the invention, the punch has a section which includes a re-entrant portion at or towards its rear, into which re-entrant portion the frame member or support carrying the die projects, so that the said re-entrant portion works over and preferably in contact with such frame member or support.

According to a further feature of the invention, the die, which has a cutting shape to co-operate with the forward and lateral surfaces of the punch, has the part of the die coming to the rear of the said punch discontinuous or open to permit the location therein of the frame or support coming to the rear of the punch.

Although the invention is not limited thereto, the section of punch it is preferred to employ is of general crescent or horseshoe shape, the re-entrant boundary at the rear being somewhat semi-circular or more precisely consists of a circumferential arc of somewhat less than 180° terminating in slightly diverging tangents, whilst the forward and lateral portions are comprised by somewhat more than a semicircle of slightly greater diameter. To co-operate with this front and lateral curvature of the punch the die has a cutting edge of similar shape the ends of which extend rearwardly to form a slot for the accommodation of the frame member, this latter having a front generally semi-cylindrical part to fit and engage in the re-entrant portion at the rear of the punch.

It is preferred so to construct nibbling machines in accordance with the invention that upon the stopping of the machine the punch is disengaged from the die, which normally would be the upper position, and for this purpose and in accordance with a further feature of the in-

vention spring means are provided, which always assure the outward stroke of the punch should the drive stop in any other position. In this manner the tool when stopped is always readily withdrawn from or re-engaged with the workpiece and further, the actual punch receives its maximum impact force when re-starting before contacting with the workpiece to be operated upon.

Devices according to the invention may be driven by any suitable means, for example by a flexible or other shaft, or even by a self-contained driving means. For example, such self-contained driving means may, in accordance with a further feature of the invention, be comprised by a pneumatic, electric or other motor wholly contained within the handle by which the device is held and manipulated in relation to the sheet of metal, or other workpiece being operated upon.

The invention comprises further features which will be apparent from the following description.

In order that the invention may be better understood, it will now be described with reference to the accompanying drawings, which are given by way of example and in which:

Fig. 1 shows in side elevation one form of nibbling machine constructed according to the invention, adapted to be operated by a pneumatic motor included in its handle.

Fig. 2 is an end view thereof, taken from the direction remote from the inlet for air.

Fig. 3 is a sectional side elevation to a larger scale of a portion of Fig. 1.

Fig. 4 is an end elevation, partly in section, of a portion of Fig. 3.

Figs. 5, 6, 7 and 8 are sections on the lines 5—5, 6—6, 7—7 and 8—8, Fig. 3.

Fig. 9 is a somewhat diagrammatic plan hereafter referred to.

Fig. 10 is a perspective view, partly in section, of the frame member.

Fig. 11 shows a diagrammatic view, in three positions, to illustrate the reciprocating drive for the punch.

Fig. 12 shows a view somewhat similar to Fig. 8 but in which the reciprocating tool does not actually wholly contact with the frame member but is somewhat spaced from the portion of the frame member which projects into the re-entrant portion of the tool.

Fig. 13 shows (to a somewhat larger scale) the operative section of another punch in accordance with the invention.

Nibbling machines according to the invention 55

can be driven from a power line, from a flexible shaft, or any suitable power-operated means. Further, they may include in their structure fluid-operated or electric motors. These fluid-operated or electric motors in preferred cases are enclosed in the handle means by which the tool is manipulated.

The tool shown in Fig. 1 is driven by a pneumatic motor (not shown in detail as it can be of any known form) enclosed and totally contained within the somewhat cylindrical handle 10, 11 being the pipe line thereof and 12 the exterior means by which the inlet valve is opened and closed. As will be appreciated, this means 12 is adapted to be pressed down by the hand gripping the handle 10 so that when so gripped the motor is started, whilst when the grip is released the motor stops.

The motor shaft either itself or another shaft driven through suitable gearing effects the drive and is denoted by a shaft 13 preferably mounted in ball bearings in the casing 10 and having an eccentrically arranged crank-pin 14, also mounted in ball bearings in a reciprocating slide 25 or plunger 15 working in a casing portion 16 arranged at right angles to the casing 10. The crank 14 is mounted in the inner race of a ball bearing the outer race of which is located in a recess 55 in the upper end of the plunger 15. As will be appreciated, when the shaft 13 rotates the crank-pin 14 causes the reciprocation of the plunger 15, the outer race of this ball bearing moving slightly from side to side in the recess 55, as will be seen from Fig. 11.

As will be realised, the casing 16 may be at any other angle than a right angle with respect to the casing 10 and even in some cases the angular relationship between the axes of the casing 10 and the casing 16 may be adjustable. In this latter case any necessary mechanical joints or other means are provided between the parts to accommodate the varied angular setting.

At its lower end the casing 16 has secured thereto by a union nut 17 a flanged frame member 18 shown in Fig. 10, to be hereafter more fully described. The front of this frame member 18 has a channel 19 extending from top to bottom, the upper portion of which is adapted to accommodate a lug or projection 20 at the front lower end of the casing 16 to enable the frame member to be precisely set in position and to prevent angular movement thereof.

Between the upper end of the frame member 18 and the lower end of the casing 16 is secured by 55 its flange 21 (also notched at 22 for the lug or projection 20) a bush 23 which extends downwards into the upper hollow portion of the framework and is recessed to receive one end of a compression spring 24, the other end abutting the lower part of the slide or plunger 15 through a collar 25.

The lower end of the said slide or plunger 15 has a bore in which is secured the upper end of a punch 26 by means of a grub screw 27 accessible through an opening 28 in the casing 16, the parts being so shaped and dimensioned that the punch has precise axial and angular setting.

The punch, which is generally cylindrical throughout its length, has at its lower end to the rear and extending a desired distance upwardly, a part removed to leave the section thereof somewhat crescent shaped as shown generally in Figs. 6, 7, 8 and 9. Particularly referring to Fig. 9, this section has a re-entrant curvature 30 at the rear part of somewhat semicircular form, or more

precisely consists of a circumferential arc of somewhat less than 180° terminating in slightly diverging tangents, and its front and lateral portions have the curvature of the exterior surface of the punch 26 which is a circle of greater diameter than that of the re-entrant portion and consequently it is of slightly greater than semicircular extent and for the purposes of description may be regarded as having a front portion 31 and lateral portions 32.

The frame member 18, as will be seen clearly from Fig. 10, has the upper hollow cap-like part terminating in the flange (to be engaged by the union nut 17) and with the upper portion of the channel 19. It further includes at its lower part 15 a circular plate-like portion 33 (with the lower portion of the channel 19) to receive on its upper surface a die 34, and the portion 33 is connected to the upper main cap-like part of the frame by a portion 35 the section of which is shown in Fig. 20 8 and comprises a front somewhat semi-cylindrical part 36 (which also extends upwards into the lower part of the cap portion and downwards into the plate 33, as shown in Figs. 3, 4 and 10) which is of such a size and so disposed in the assembly that it enters into the re-entrant portion 30 of the punch and forms a support and guide therefor. The portion 35 extends rearwardly, its sides 37 converging regularly or otherwise from the semi-cylindrical front 36.

The die 34 is formed from a circular plate having its cutting edge 38 to co-operate with the front and sides 31 and 32 of the punch and the terminations of this cutting edge are slightly widened and extended rearwardly by surfaces 39 35 to form a slot 40 as shown in Fig. 8. This slot permits the die to be positioned with the portion 35 of the frame in the slot.

41 is a cap member having a slot 42 extending diametrically across its base, the front of which 40 slot coincides with the lower part of the channel 19. The side walls of this cap fit around the plate portion 33 and the die 34, which is of the same diameter as the plate, to act as part locating means for the said die. The parts are fully located and secured in position by screws 43 which engage in the base of the cap, pass through bores in the plate portion 33 and enter suitably tapped apertures 44 in the die.

The lower part of the cap portion of the frame 50 18 comes a desired distance above the upper surface of the die to leave an entry aperture or mouth 45 for the tool to be passed on to the metal sheet such as 46 or other workpiece and it should be observed from Fig. 3 that the die has an upper 55 surface with a flat portion 47 adjacent its cutting edge, the rest of the surface being slightly coned at 48.

The operation will be readily understood. In the first place it should be observed that the compression spring 24 assures that when the machine has stopped the plunger 15 and punch 26 have been brought to the upper position. This enables the mouth 45 fully to be passed on to the edge of the metal sheet 46 so that the said edge contacts with the front semi-cylindrical portion 36 of the frame portion 35, with the lower end of the punch above the metal sheet. This position is shown clearly in Fig. 3. When the machine is started with the punch in this position it has been 70 found that the impact is ample to commence the cut. The first punching falls through the lower part of the channel 19 and the slot 42. By the forward pressure of the hand holding the tool, when the punch again attains its upper position, 75

the semi-cylindrical portion 36 of the frame part 35 is pushed forwards to make contact with that part of the sheet metal which has been cut by the front part 31 of the punch and then the action is repeated. In the result and as shown in Fig. 9, a cut 49 is made in the sheet 46 by the series of rapidly following punching operations, the edges of the cut having slight undulations due to the lateral portions 32 of the punch.

10 The cut can follow any desired line as the converging portions 37 of the frame member 35 permit curves of comparatively small radius to be cut. Again, the workpiece such as the sheet metal 46 need not have a plane conformation as 15 the mouth 45 and die 34 with bevelled surface 48 enable sheets or the like of curved conformation also to be dealt with.

It should also be appreciated that as the hand 20 grasping the casing 10 (which in practical tools is about four inches long, the other parts being in proportion) comes closely adjacent the work and as moreover there are substantially no unbalanced 25 masses, even a comparatively unskilled operator can utilise the tool with great precision and follow intricate paths of cut including turns with facility.

Finally, in connection with the operation it should be understood that the relative shaping 30 and juxtaposition of the punch and the frame portion 35 give practicability and long life to the tool. The main reason for this is that the breaking or bending leverage on the frame portion 35, due to the downward thrust of the punch on the metal which is transferred to the die, meets with 35 a maximum possible resistance due to the fact that a strong section of the frame portion 35, i. e., the somewhat semicircular section 36, enters into the re-entrant portion of the punch and thus reduces the effective leverage to a minimum.

40 In addition to the numerous advantages of a tool constructed according to the invention which can be gathered from the preceding description, can be mentioned the fact that the frame member 18 is detachable by removing a single fixing means, that is the union nut 17.

45 In some cases a collector may be provided for the punchings, such for example as indicated in dotted lines at the lower part of Fig. 2, where 50 is a hollow cylindrical container of desired length, which can be attached to the exterior of the cap 50 41 by a screwed bayonet or other joint into which the punchings can fall through the slot 42.

Although the section of the punch shown in the drawings is one which in practice has given good 55 results, it is to be understood that the re-entrant portion can be other than a bend or curve. For example, it may be of angle, channel or other form, or any desired combination thereof. Similarly, the front and lateral portions of such section 60 may be varied, but preferably the lateral portions are convergent.

In the form shown in Fig. 13, the punch has a somewhat hexagonal section the re-entrant portion being a channel with diverging walls 56 whilst the exterior has the ends 57 of the lateral portions flat and convergent.

Again, variations may take place in the construction of the die. For example, only substantially the front half in the particular construction 70 described need be used and the slot 40 replaced by a space. Further, in place of screws such as 44, other means can be utilised to keep a die having only an active front part and a discontinuous or open rear part, or even without such rear part, in 75 position.

Further, instead of being located by a cap other means may be employed and the front shape may also be varied.

Although for most purposes it is preferred that the tool having the re-entrant portion by its rear 5 surface should ride in contact with the portion of the frame member with which it co-acts, yet such actual contact may not be necessary. For example, in some cases, the frame member although projecting into the re-entrant portion, may not 10 actually contact therewith. Such an example is shown in Fig. 12, from which it will be seen that although the actual construction is somewhat similar to that shown in Fig. 8, yet the projecting part of the frame member 36 does not form a 15 bearing surface for the re-entrant curved surface of the tool. However, it is preferred that the rearmost edges of the said tool should have a guide, for example by the stepped formation 54.

The invention is not limited to the precise forms 20 or details of construction described, as these may be varied to suit particular cases.

What I claim and desire to secure by Letters Patent of the United States of America is:

1. A nibbling machine combining a relatively 25 fixed frame member, a reciprocating punch carried thereby and a cooperating die, the said frame member extending to one side of but adjacent the reciprocating punch, said punch having an operative punching section including a re-entrant portion 30 towards the extending frame member into which re-entrant portion a part of the frame member projects for the purpose set forth.

2. A nibbling machine as claimed in claim 1, in which the die has only active front and lateral 35 portions, the other portion being free of the frame member.

3. A nibbling machine as claimed in claim 1 in which the punch has an operative section of substantial crescent shape.

4. A nibbling machine as claimed in claim 1, in which the re-entrant portion of the punch consists of a circumferential arc of somewhat less than 180° terminating in slightly diverging tangents, and in which the front and lateral portions 45 of the said section are formed by the arc of a circle of somewhat larger diameter and slightly more than a semicircle in extent.

5. A nibbling machine as claimed in claim 1, in which the frame member has a substantially 50 semi-cylindrical front portion to be received into the re-entrant portion of the punch.

6. A nibbling machine as claimed in claim 1, in which said frame member extends rearwardly from the portion engaging in the re-entrant part 55 of the punch, said rearwardly extending portion being converging in cross section.

7. A nibbling machine combining a relatively fixed frame member, a reciprocating punch carried thereby and a cooperating die, said punch 60 having a re-entrant portion, said frame member having spaced-apart upper and lower portions substantially axially arranged with respect to the punch, and an integral connecting portion having a part shaped to coact with the re-entrant 65 portion of the punch, the upper portion of the frame being detachably attached and the lower portion carrying the die thereby to leave a mouth above the die to be engaged with the work-piece.

8. A nibbling machine as claimed in claim 7, 70 in which the shaped part of the connecting frame portion which engages in the re-entrant part of the punch, extends into the upper and lower frame portions.

9. A nibbling machine as claimed in claim 7, 75

in which the die-carrying frame member is connected by a nut member.

5 10. A nibbling machine as claimed in claim 7, in which spring means are associated with the reciprocating punch for assuring the disengagement of the punch from the die.

11. A nibbling machine as claimed in claim 1, in which the die is carried by a circular plate-like part of the frame member, and a cap with attach-

10 ing screws for said part.

15 12. A nibbling machine as claimed in claim 1, in which the machine is provided with a manipulating handle and a driving motor operatively connected with the punch and housed in said handle.

13. A nibbling machine as claimed in claim 1, in which the re-entrant portion of the punch works in contact with the frame member.

14. A nibbling machine as claimed in claim 1, in which the punch includes a re-entrant portion which consists of a front portion and another portion extending both laterally and rearwardly from said front portion, the re-entrant portion being directed towards the extending frame member and into which re-entrant portion a part of the frame member projects for the purposes set forth.

15. A nibbling machine as claimed in claim 1, 10 in which the part of the die which cooperates with the punch has a front portion and side portions, which latter extend both laterally and rearwardly, the other portion of the die being free of the frame member.

GEORGE HENRY WEBB.

15
